(57) **CLAIM**

The ornamental design for an electric motorbike motor cover, as shown and described.

DESCRIPTION

FIG. 1 is a front end and right side perspective view of an embodiment of an electric motorbike motor cover;

FIG. 2 is a right side elevational view thereof;

FIG. 3 is a left side elevational view thereof;

FIG. 4 is a rear end elevational view thereof;

FIG. 5 is a front end elevational view thereof;

FIG. 6 is a bottom plan view thereof; and,

FIG. 7 is a top plan view thereof.

The broken line showing of attachments to the electric motorbike motor cover is included for the purpose of illustrating environmental structure and forms no part of the claimed design.

1 Claim, 6 Drawing Sheets
